UNITED STATES PATENT OFFICE.

CLARENCE W. BENNETT, OF NEW YORK, N. Y., ASSIGNOR TO ARDEN MANUFACTURING CORPORATION, OF NEW YORK, N. Y., A CORPORATION OF NEW YORK.

DESIGN FOR A TOY AEROPLANE.

53,214.

Specification for Design.

Patented Apr. 22, 1919.

Application filed January 18, 1919. Serial No. 271,926. Term of patent 3½ years.

To all whom it may concern:

Be it known that I, CLARENCE W. BENNETT, a citizen of the United States, residing at New York city, New York, have invented a new, original, and ornamental Design for Toy Aeroplanes, of which the following is a specification, reference being had to the accompanying drawing, forming a part thereof.

The figure is a perspective view of a toy aeroplane showing my new design.

I claim:

The ornamental design for a toy aeroplane, as shown.

CLARENCE W. BENNETT
